UNITED STATES PATENT OFFICE.

WILLIAM H. MCCOY, OF MILLER'S FALLS, MASSACHUSETTS.

IMPROVEMENT IN CHUCKS.

Specification forming part of Letters Patent No. 146,262, dated January 6, 1874; application filed June 20, 1873.

To all whom it may concern:

Be it known that I, WILLIAM H. McCoy, of Miller's Falls, in the county of Franklin and in the State of Massachusetts, have invented certain new and useful Improvements in Chuck for Drills, &c.; and do hereby declare that the following is a full, clear, and exact description thereof, reference being had to the accompanying drawings, and to the letters of reference marked thereon, making a part of this specification.

The nature of my invention consists in the construction and arrangement of a chuck for drills, as will be hereinafter more fully set forth.

In order to enable others skilled in the art to which my invention appertains to make and use the same, I will now proceed to describe its construction and operation, referring to the annexed drawings, in which—

Figures 1 and 2 are longitudinal sections of my chuck. Fig. 3 is a side view of the stock. Fig. 4 is an end view of the entire chuck; and Fig. 5 shows one of the jaws.

A represents the stock of my chuck, provided with a hole or cavity at one end for the insertion of the handle B. This part of the stock is cylindrical, with screw-threads around it for the sleeve C to be screwed on the same. The lower part of the stock A is tapering, as shown in Fig. 3, and the corresponding part of the sleeve is made in the same manner to fit snugly over it. The tapering part of the stock A is slotted at right angles for the reception of the jaws D D, and from the upper end of each slot

a groove, b, extends up to and through the upper end of the stock. Each jaw D is made in wedge form with the point cut off, as shown in Fig. 5, and near the base of the jaw is made a slot, e, for the insertion of a dowel to hold the jaw in the slot on the stock, said slot having a corresponding enlargement for the dowel. The dowel used may be a spiral spring, d, as shown in Fig. 2, which thus, in addition to its office as a dowel, will act as a spring to throw the jaw outward when the sleeve C is loosened; or a solid dowel, d', may be used, as shown in Fig. 1, in which case a spring or spring-wire, h, is fastened in the groove b on the stock, and the end inserted in a hole, i, in the end of the jaw. For smaller chucks this latter will be best, as it does not necessitate such a large slot in the jaw, but for larger chucks I prefer to use the spiral-spring dowel.

Having thus fully described my invention, what I claim as new, and desire to secure by Letters Patent, is—

The combination of the stock A, slotted jaws D D with dowels in their slots, springs h h, and the sleeve C, all constructed and arranged substantially as and for the purposes herein set forth.

In testimony that I claim the foregoing I have hereunto set my hand this 24th day of May, 1873.

WM. H. MCCOY.
